H. G. Manning

UNITED STATES PATENT OFFICE

JOSEPH C. WRATSCHKO, OF NEW BRITAIN, CONNECTICUT

DOOR LOCK SET

Application filed December 27, 1929. Serial No. 416,804.

This invention relates to door lock sets, and more particularly to a lock set in which the door may be unlatched by turning the knob in one direction, and locked against further unlatching by turning the knob in the other direction.

One object of the invention is to provide a device of the above nature, in which the parts will be restored to their original unlocked position by the use of a key-operated cylinder or other device.

A further object is to provide a device of the above nature which will be relatively simple in construction, inexpensive to manufacture, easy to install and manipulate, compact, and very efficient and durable in use.

With these and other objects in view there has been illustrated on the accompanying drawings one form in which the invention may be conveniently embodied in practice.

Fig. 1 represents an elevation of the lock set as viewed from the inside of the door with the cover of the casing removed and showing the door frame in section, the door being latched but unlocked.

Fig. 2 is a view similar to Fig. 1 but showing the door in locked position with the lug on the key-operated cylinder ready to engage the sliding frame to unlock the door.

Fig. 3 is an end elevation of the door, with the front part of the casing broken away to show the interior construction.

Fig. 4 is a horizontal sectional view taken along the line 4—4 of Fig. 1 looking downwardly.

Referring now to the drawings in which like reference numerals denote corresponding parts throughout the several views, the numeral 10 indicates a door having a rectangular cavity 11 for receiving a lock casing 12, said casing being located in alignment with a catch recess 13 formed in the door frame 14. The door frame 14 has a flat metal plate 15 located in the front of said recess

13, said plate 15 having an aperture 16, the length of which is somewhat shorter than that of the recess 13, for a purpose to be hereinafter described. Located within the casing 12 is a horizontal latch bolt 17 having a slot 18 fitted around a pin 19 adapted to guide

the rear part of the bolt in its sliding motion.

In order to permit the latch bolt 17 to be retracted into the casing, said bolt 17 is provided with a rear flange 20 adapted to be engaged by the extremity 21 of an upwardly extending arm 22 carried on a hub 23, said hub having a squared aperture 24 fitting a square handle-operated rod 25. The hub 23 is also provided with a downwardly-inclined arm 26 located at about 150 degrees from said arm 22, and both of said arms 22 and 26 are adapted to be resiliently engaged by a spring 27, one extremity of which is fixed within a block 28 secured to the casing 12.

By means of this construction, the arm 22 will tend to remain in the neutral position shown in Fig. 1 at all times, and will be returned to said position automatically by said spring 27 whenever the handle-operated rod 25 is released after being turned in either direction.

The outer end of the latch bolt 17 is provided with an enlarged downwardly extending latch member 29, having its outer face 30 beveled at an angle of about 45 degrees, whereby when the door is being closed, the latch bolt 17 will be moved rearwardly into the casing 12 by the striking of the beveled face 30 of the latch member against the vertical edge of the plate aperture 16.

Pivottally mounted on a pin 31 projecting from the intermediate portion of the latch bolt 17 is an upper locking member 32 having an upwardly extending foot 33 adapted to lie flush with the end of the latch member 29 when the parts are in the unlocked position, as shown in Fig. 1. A lower locking lever 34 is also provided, being pivoted to a depending portion of the latch member 29 on a pin 35, and said lower locking member 34 is connected to the upper locking member 32 by a link member 36, as most clearly shown in Fig. 1. The lower locking lever has a depending foot 37 similar to the foot 33.

By means of this construction, it will be seen that when the upper locking member 32 is swung upwardly into its locking position, the lower locking member 34 will also be swung downwardly. This will cause the feet 33 and 37 to spread apart and lie behind the

edge of the plate aperture 16, thus locking the latch bolt 17. When the parts are in this position, it will be impossible to unlatch the door by turning the handle knob in either direction.

5 Normally, the locking levers 32 and 34 will be maintained in the unlocked position shown in Fig. 1 by the action of a pair of springs 38 and 39. The spring 38 engages one end of a 10 curved finger 40 on the latch bolt 17, and has its other end located in a slot 40a adjacent a semi-circular section 41 of said upper locking lever 32. The lower spring 39 is secured at one end to a block 42 on a sliding frame 15 43 and the other end of said spring 39 presses to the right against a shoulder 44 on the depending latch member 29.

In order to prevent the locking levers from returning to the unlocked position shown in 20 Fig. 1, said sliding frame is provided at its upper edge with a vertical slot 45 adapted to fit about an arm 46 depending from the lower edge of the upper locking lever 32. The sliding frame 43 is pressed upwardly at 25 all times by a spring 47 having one end fixed in a block 48 located on said casing 12.

Operation

In operation, when the door is closed, the 30 latch bolt 17 will first be retracted into the casing by the engagement of the beveled face 30 with the edge of the aperture 16, and will then snap back into the catch recess 13. When it is desired to again open the door, it may be 35 unlatched merely by turning the handle-operated rod 25 in a counter-clockwise direction, as viewed in Fig. 1, thus retracting the latch bolt 17 into the casing 12.

When it is desired to lock the door, it will 40 only be necessary to turn the handle-operated rod clockwise, as viewed in Fig. 1, whereupon the arm 22 of the hub 23 will engage the rear edge 49 of the upper locking lever 32, causing said lever 32 as well as the lower lever 45 34 to swing from the positions shown in Fig. 1 to the spread-apart positions shown in Fig. 2. The rotation of the locking lever 32 as just described will bring the depending arm 46 thereof into alignment with the slot 45 in the sliding frame 43, permitting said frame 43 to be moved upwardly automatically by the spring 47, thus preventing the locking levers from moving back to their unlocked position shown in Fig. 1.

55 When it is desired to unlock the door, it will only be necessary for the operator to insert the key, not shown, into a cylinder 50 having a side lug 51, and to rotate said cylinder in a clockwise direction until said lug 51 engages an inclined projection 52 on the bottom of the sliding frame 43. The frame 43 will thus be caused to move downwardly until the slot 45 is disengaged from the arm 46. 60 This will permit the springs 38 and 39 to

move the locking levers 32 and 34, from the locked position shown in Fig. 2 to the unlocked positions shown in Fig. 1. The frame 43 will thereafter be held from moving upwardly by the arm 46.

70 While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of 80 the following claims.

Having thus fully described the invention, what is claimed as new, and for which it is desired to secure Letters Patent, is:

1. In a door lock set, a door casing adapted to lie in alignment with a door frame catch recess, a manually operated rod passing through said casing, a latch bolt in said casing and normally seated in said recess when the door is closed, means connected to said rod for retracting said latch bolt when said rod is turned in one direction, a lever pivoted to said latch bolt for swinging into locking engagement with said recess when the rod is turned in the opposite direction, a link pivotally connected to said lever, and a second lever pivoted to said link for also swinging into locking engagement with said recess simultaneously with said first lever.

90 2. In a door lock set, a door casing adapted to align with a door frame catch recess, a sliding latch bolt in said casing for engaging with said recess, manually-operated means for retracting said bolt when moved in one direction for permitting the door to be opened, means on said bolt to be engaged by said manually-operated means to lock said bolt within said recess when moved in another direction, and a frame slidable at 95 right angles to said latch bolt for retaining said bolt in locked position until released by a key.

100 3. In a door lock set, a door casing adapted to lie in alignment with a door frame catch recess, a manually-operated rod passing through said casing, a latch bolt in said casing and normally seated in said recess when the door is closed, means connected to said rod for retracting said latch bolt when said rod is turned in one direction, a lever pivoted to said latch bolt for swinging into locking engagement with said recess when the rod is turned in the opposite direction, a frame within said casing slidable transversely to said latch bolt for preventing said lever from moving into locking engagement with said recess when said rod is turned in the first direction.

115 4. In a door lock set, a door casing adapt-

ed to lie in alinement with a door frame catch recess, a manually-operated rod passing through said casing, a latch bolt in said casing and normally seated in said recess when the door is closed, means connected to said rod for retracting said latch bolt when said rod is turned in one direction, a lever pivoted to said latch bolt for swinging into locking engagement with said recess when the rod is turned in the opposite direction, a frame within said casing slidable transversely to said latch bolt for preventing said lever from moving into locking engagement with said recess when said rod is turned in the first direction, said lever having a depending lug, and said frame having a slot to receive said lug for preventing said lever from being moved out of locking engagement with said recess.

20 In testimony whereof, I have affixed my signature to this specification.

JOSEPH C. WRATSCHKO.
